UNITED STATES PATENT OFFICE.

HENRY H. CUTLER, OF BROOKLINE, MASSACHUSETTS.

INTERNAL-COMBUSTION ENGINE.

Application filed November 4, 1924. Serial No. 747,746.

My invention relates to internal combustion engines and more especially to such engines of the variable clearance type in which means are provided for varying the clearance space in unison with the movement of the power piston whereby the volume of such clearance space is made to vary in such close relation to the load on the engine that the degree of compression may be maintained approximately constant at all loads.

A further object of my invention is to utilize the same mechanism for mechanically scavenging the cylinder after every explosion, and a still more important object of my invention is to provide a very large amount of resilient recoil at the time of each explosion of the working mixture in the engine cylinder whereby the strain upon the crank shaft and the reciprocating parts is reduced to from one-half to one-third of the normal initial pressure thus making it practical to employ a compression pressure twice as high as possible in the usual form of combustion engine, without producing knocking or destructive wear.

The present invention is a further development of that disclosed in my pending application Serial No. 701,051, filed March 22, 1924.

The principal feature of my invention is the provision of an air reservoir from which the air cannot escape during the operation of the engine, and the still further utilization of the same mechanism for automatically supplying to the said air reservoir, air compressed to any pressure desired under the control of the operator, said compressed air being utilized to control the resulting and corresponding degree of compression in the engine cylinders.

Figure 1 is a central vertical section of one of the cylinders of an internal combustion engine, embodying my invention and showing the relative position of the moving parts on completion of the scavenging or exhaust stroke of the power piston of the engine.

Fig. 2 is a partial vertical section taken on line 2-2 of Fig. 1 and showing a diaphragm pressure regulator, controlled by a rod extending to the instrument board under the control of the operator;

Fig. 3 is a horizontal section taken on the line 3-3 of the pressure regulator showing the means for admitting air from the atmosphere into the space 77 of the engine cylinder.

In the drawings I show in place of the usual demountable head, a single unit head consisting of the casting 17 secured by bolts 17' to the top of the cylinder block 14 in the usual manner. In the casting 17, cylinders 18, etc., are formed and constitute extensions of the corresponding cylinders of the main engine block 14. Midway in each of these cylinder extensions is a fixed head or plug 22, each head being hollow and connected with the water-jacket by passageways 26, 26.

It is essential that these fixed heads 22 shall make a gas and water-tight joint with the walls of the cylinder in which they are placed. This result I obtain by accurately grinding the heads 22 a few thousandths of an inch larger in diameter than the bore of the cylinder extensions 18, then heating the entire cylinder casting 17 and placing the heads 22 therein cold, so that when the cylinder casting 17 cools, the heads 22 are firmly gripped. This process I have found in practice to be sufficient not only to make a perfect water and gas-tight joint, but also to stand the pressure of the exploded gases under working conditions.

Arranged for longitudinal movement in each cylinder 18 is a member 28, the portion or volume of each cylinder 18 between each power piston 32 and said movable member 28 forming a compression chamber 75, and means are provided for automatically controlling the position of said movable member 28 so as to vary the volume of said compression chamber 75 in practically exact accordance with the variation of the load on the engine, thus keeping the degree of compression approximately the same at all times. The position of said movable member 28 is controlled automatically and resiliently for the purpose above specified and after each explosion of the working mixture the position of said movable member 28 is automatically changed so as to greatly enlarge the volume of the compression chamber 75, and thereby greatly reduce the resulting pressure of the exploding gases upon the crank shaft and reciprocating parts of the engine.

At the completion of the power stroke the movable member 28 has been automatically moved towards the power piston 32 and smoothly brought to a stop in such position as to effect almost complete mechanical scavenging of the engine cylinder on the completion of the exhaust stroke of the power piston 32, as shown in Fig. 1.

- Arranged for longitudinal movement in the top part 37 of each cylinder extension 18 is another movable member or dash-pot piston 39. Each dash-pot or pressure piston 39 is connected with its respective scavenging piston 28 by means of a long rod 40. Said rod is preferably made of hardened steel and works up and down in a long bushing 40' made preferably of bronze bearing metal in which bushing 40' the steel rod 40 makes a free but close fit that is nearly, if not entirely, airtight. The lower end of said rod 40 has a head 41 and is held to the scavenging piston 28 by means of a washer 42 riveted to the bottom of the piston 28 with rivets 43. In the bottom of the rod 40 is shown a cylinder 45 arranged to slide freely in a hole in the rod 40 and pressed up by a spring 46. The lower end of the cylinder 45 terminates in a rod 47 to which is riveted a conical valve 48 after the rod 40 has been attached to the piston 28 so as to form a small valve free to open into the space 75 whenever the pressure in the compression chamber 76 exceeds the pressure in the chamber 75.
- The pressure piston 39 also contains one or more small valves 50 held down by a spring 51 seating on the inside of the piston 39 and free to open whenever the pressure in the chamber 77 (formed between the bottom of the pressure piston 39 and the top of the head 22) exceeds to a predetermined degree the pressure in the air reservoir or chamber 78 above the pressure piston 39. Inserted in a circular chamber turned out in the top of the plug head 22 is a coil of insulated wire 53. The inside terminal of this wire coil is welded to a thin brass tube 54^a made to fit closely over the central pole 54 of the circular electromagnet formed in the end of the plug-head 22. The outside terminal 53^a of the coil 53 passes through a hole drilled in the plug head 22 and then through a threaded hole 55 drilled through the cylinder 37 opposite the hole in the head 22. A threaded bushing 56 of tough insulating material is screwed up solid against some asbestos thread packing surrounding said terminal 53^a where it passes through the holes drilled in the plug 22 and cylinder 37, thereby forming a permanent airtight packing around said terminal wire of the coil 53. A brass disc 58 is pressed down against shoulders cut in the inside and outside poles of the electromagnet so as to make a practically airtight fit. The depth of said shoulders is preferably such that the top surface of the brass plate 58, when in position, will be about one-hundredth of an inch lower than the surface of the inside magnet pole 54 so that when the pressure piston 39 makes mechanical contact with said central pole 54, a minute air chamber 77 is formed between the bottom of said piston 39 and said brass plate 58.
- The size of said minute air chamber 77 of

course will depend upon the size of the engine, but for an engine having a bore of 3 3/4", the size of chamber 77, above mentioned, would be approximately correct.

The pressure piston 39 is preferably made of a non-magnetic material such as phosphor bronze, and is provided with a steel disc 39' mounted on the bottom of the piston 39, as clearly shown in Fig. 1.

Before the final assembling is made of the above mentioned parts, and before the plug 22 is shrunk into the casting 17, as previously explained, the steel rod 40 is passed through the bushing 40' in the plug 22 and the pistons 28 and 39 are clamped firmly together by means of the nut 44 in the position shown in Fig. 1. The steel plate 39' is then ground against the central pole 54 of the electromagnet so as to make an airtight valve for the purpose of preventing any possible escape of air from the reservoir 78 by the outside of the piston 39 under the steel plate 39' and around the long rod 40 inside the bushing 40'. This arrangement is an essential feature of my invention as any appreciable escape of air from the reservoir 78 during the operation of the engine would constitute an impractical and uncommercial device.

The above mentioned parts are then permanently assembled as shown in Fig. 1 and the cover-plate 61 electric welded to the casting 17, as shown, thereby making an absolutely airtight joint. A cap 63 is shown threaded into the head 67 to afford access to the interior thereof for adjusting the springs 51 when desired.

Screwed into the side of each cylinder 18 above the plug 22 is an automatic air valve casing 91 containing a valve 92 held to its seat by a spring 93 and arranged to open inwardly whenever the pressure in the chamber 77 (formed between the bottom of the piston 39 and the brass plate 58) falls below that of the outside atmosphere.

The valve casing 91 is shown connected by a rubber tube 96 with the outlet opening 112' of the diaphragm controlled regulator.

This pressure regulator, Fig. 2, is shown mounted on two projecting lugs 101 and 102 cast on the cover 61. The lug 101 has a circular opening on the side covered by a metallic disc 103 permanently welded to it so as to form an airtight joint. The inside of the disc 103 is subjected to the pressure of the air in the reservoir 78 by means of the hole 104 drilled as shown through the cover 61.

A disc 105 is pressed against the outside of the diaphragm 103 by means of an adjustable spring 106. The strength of the spring 106 may be adjusted by screwing the threaded wheel 107 on the threaded spindle 108, which spindle is shown fastened to the lug 102 by the screws 109. The wheel 107

has teeth cut so as to mesh with teeth cut in the rod 110 which is designed to pass over the engine to the instrument board where it may be reached and turned handily by the operator. Inside the spindle 108 is shown a long rod 111 having one end in the form of a conical valve arranged to close the valve seat 112 and thereby shut off the opening 112'. The other end of the rod 111 seats in the disc 105. Another rubber tube 113 connects the opening 112' with an air filter (not shown) used preferably in connection with the carburetor to filter all the air used either in the engine proper or supplied to the air reservoir 78. Back of the valve seat 112 is drilled a hole 114 (Fig. 3) and central with this hole 114 is shown a threaded nipple 115 screwed into the main casting 102. This nipple 115 is shown surrounded by one end 29 of the rubber tube 96 the other end of said rubber tube 96 being connected, as shown in Fig. 1, to the valve casing 92. Whenever the pressure of the air against the diaphragm 103 is insufficient to keep the valve 111 pressed against its seat 112, air is free to be drawn into the space 77 by way of the opening 112', passage 114 and rubber tube 96. Each cylinder of a multiple cylinder engine is preferably equipped with an automatic intake air valve 91 which is connected by rubber tubing 96 or any other convenient way to one diaphragm regulator, Fig. 2, so that when the pressure of the air in the reservoir 78 is sufficient to force the disc 105 from its seat and close the valve seat 112, no more air will be pumped into the reservoir 78.

The operation of the engine is as follows:

The engine is started by first closing the circuit to the electromagnet coils 53 by means of the rheostat lever 72 and then turning over the engine either by hand or with a small electric motor in the usual manner. As the power piston 32 approaches the scavenging piston 28, sufficient compression is developed to force the pressure piston 39 away from its seat against the pull of the electromagnet 53 which is preferably kept constantly energized. The piston 39 being thus released from the electromagnet allows both pistons 28 and 39 to move suddenly up and away from the power piston 38 until this movement is stopped by the compression of the air in the chamber 76. The minute amount of air in the chamber 77 formed between the bottom of the pressure piston 39 and the brass plate 58 immediately expands to a pressure far below that of the outside atmosphere causing the air valve 92 to open and admit fresh air into the chamber 77. The power piston 32 then descends, being forced down by three different sources of power.

First. The compression of the air in the chamber 76. Second. The difference between

atmospheric pressure above the pressure piston 39 and less than atmospheric pressure below the piston 39. Third. The driving power of the electric motor starter.

The pressure piston 39 now approaches its seat against the central pole 54 of the electromagnet. In so doing the air which has been sucked in through the air valve 92 is compressed in the now minute air chamber 77 acting as a cushion against the pull of the magnet which finally pulls the piston 39 against the central port 54 of the electromagnet. This process is repeated until finally so much air has been sucked in through the air valve 92 that it becomes sufficiently compressed to open the valves 50 and thus the engine begins to force air into the reservoir 78. By this time the engine will probably have started, operating under a compression pressure in excess of twenty pounds. This compression pressure is the sum of the difference in air pressure above and below the piston 39 and the air compressed in the chamber 76, and can be increased or diminished in accordance with the size determined upon of the chamber 76.

The engine can now be brought up to speed and air will then be rapidly forced into the reservoir 78 until sufficient pressure has been developed in said reservoir 78 to force the disc 105 from its seat and thus shut off communication with the atmosphere by means of the valve 111 so that no more fresh air can be pumped into the reservoir 78.

It is evident that the electromagnet is not called upon to exert sufficient power to compress air at atmospheric pressure to the pressure in the reservoir 78, but merely has to exert sufficient pulling power to overcome the difference in air pressure between the top and bottom of the piston 39 sufficient only to overcome the pressure of the springs 51 which hold down the little valves 50 upon their seats. The strength of these springs 51 is sufficient to cause an increase of air pressure in the chamber 77, great enough to act as a cushion to prevent the piston 39 from hammering against its seat 54 of the electromagnet. This tendency of the pistons 39 to hammer against the central pole 54 of the electromagnets is further subject to perfect control by means of the rheostat 69 so that the engine will run quietly and the reciprocating pistons 28 and 39 are thus brought resiliently and quietly to rest at both extremes of their travel up and down. After the air reservoir 78 has been filled with air at the desired pressure, the electromagnets are called upon to return to the reservoir 78 only such air as manages to leak by the piston 39 during the power stroke of the engine. Should any air manage to leak out of the reservoir 78, the diaphragm regulator, Fig. 2, will cause the

valve 111 to open and the engine will then automatically begin to supply additional air.

Keeping the electromagnets energized continuously during the operation of the engine not only does away with extra circuit controlling devices, but also possesses another very decided advantage, namely, the pistons 28 and 39 possess more or less weight and a very large moment of inertia, especially when the engine is operated at high speed, by keeping the electromagnets permanently energized, the pistons 28 and 39 start to move quickly the moment they are released from the electromagnet, and this is followed by the firing of the mixture so shortly afterwards that the pistons 28 and 39 do not have time to stop their upward motion. The kick of the explosion against the crank shaft is thus still further reduced because it is not called upon to immediately start to move the weight of the pistons 28 and 39 from a position of rest.

By the addition of practically one moving part, namely, the pistons 28 and 39 rigidly connected by the rod 40, this part performs no less than five different uses. First, it automatically supplies compressed air to any desired pressure for the reservoir 78, thereby determining the compression pressure of the engine. Second, it thoroughly scavenges the engine of the inert exhaust gases usually left over in the engine cylinder at the completion of the exhaust stroke. Third, it provides a very large amount of resilient recoil at the instant of each and every explosion of the working mixture thereby greatly diminishing the resulting mechanical strains upon the engine mechanism and correspondingly increasing the life of its vital parts. Fourth, it greatly increases the economy of the engine by making it practical to use very high compression pressures. Fifth, it still further increases the economy of the engine by maintaining a high compression with a reduced volume when operating under lighter loads than full load.

I claim—

1. An internal combustion engine comprising in combination a cylinder, a hermetically sealed cylindrical chamber secured to and forming an extension of said cylinder, a piston reciprocable in and closely fitting said chamber, an automatic air intake valve and means whereby the reciprocating action of said piston will draw air into said sealed chamber until said air has been compressed in said sealed chamber to any pressure desired by the operator.

2. An internal combustion engine comprising in combination a cylinder, a hermetically sealed cylindrical chamber secured to

and forming an extension of said cylinder, a piston of non-magnetic material, a disc of magnetic material attached to said piston and of smaller diameter than said piston, and magnetic means for forcing back into the inward portion of said hermetically sealed chamber, gaseous leakage around said piston.

3. An internal combustion engine comprising in combination a cylinder, a hermetically sealed cylindrical chamber secured to and forming an extension of said cylinder, an air intake valve, a piston of non-magnetic material reciprocable in and closely fitting said cylindrical chamber, a disc of magnetic material attached to and preferably of smaller diameter than said piston, and magnetic means whereby the air that is drawn in by the action of the engine when running is forced into said hermetically sealed chamber until any pressure desired is obtained.

4. An internal combustion engine comprising in combination a cylinder, a hermetically sealed cylindrical chamber secured to and forming an extension of said cylinder, a piston closely fitting said cylindrical chamber and reciprocable therein, an air valve so located that the outward motion of said piston during the operation of the engine will tend to draw air in underneath said piston, and an air conduit connected to a pressure regulator, which will automatically shut off the supply of air when said air has been compressed in said sealed chamber to the desired degree.

5. An internal combustion engine comprising in combination a cylinder, a fixed head intermediate the ends of said cylinder, a power piston in said cylinder on one side of said head, a scavenging piston located between said head and said power piston, a dash-pot piston on the other side of said head, a rod passing through said head and rigidly connecting said scavenging and dash-pot pistons, a hermetically sealed cylindrical chamber forming an extension of said cylinder, said dash-pot piston being reciprocable in and closely fitting said chamber, an automatic intake valve so located that the reciprocating motion of said dash-pot piston during the operation of the engine will cause fresh air to be drawn in through said air valve underneath said dash-pot piston, and magnetic means for forcing said fresh air to the other side of said dash-pot piston into said sealed chamber until any desired degree of compression is obtained.

In testimony whereof, I have hereunto subscribed my name this 3rd day of November, 1924.

HENRY H. CUTLER.
